[57] CLAIM

The ornamental design for a liquid container, as shown and described.

DESCRIPTION

FIG. 1 is a perspective view of a liquid container embodying our new design;

FIG. 2 is a right side elevation, the left side elevation is a mirror image thereto;

FIG. 3 is a front elevational view thereof;

FIG. 4 is a rear elevational view thereof;

FIG. 5 is a top view thereof; and,

FIG. 6 is a bottom view thereof.

The broken lines in the drawings are for illustrative purposes only and do not form part of the claimed design.
